UNITED STATES PATENT OFFICE.

EDWARD WARREN AND GEORGE W. HEALY, OF FORT THOMAS, ARIZONA
TERRITORY.

STILL.

SPECIFICATION forming part of Letters Patent No. 714,339, dated November 25, 1902.

Application filed April 17, 1902, Serial No. 103,420. (No model.)

To all whom it may concern:

Be it known that we, EDWARD WARREN and GEORGE W. HEALY, citizens of the United States, residing at Fort Thomas, in the county of Graham and Territory of Arizona, have invented certain new and useful Improvements in Stills; and we do declare the following to be a full, clear, and exact description of the invention, such as will enable others skilled in the art to which it appertains to make and use the same.

The invention relates to stills, and more particularly to that class of devices designed for distilling water.

15 The object of the invention is to provide a device of this character which shall be simple of construction, durable in use, comparatively inexpensive of production, and which is designed to be placed upon an ordinary 20 cook-stove for the purpose of heating the water and boiling it.

With this object in view the invention consists of certain novel features of construction, combination, and arrangement of parts, which 25 will be hereinafter more fully described, and particularly pointed out in the appended claims.

In the drawings, Figure 1 is a longitudinal sectional view through the device. Fig. 2 is 30 an enlarged detailed sectional view through the end of the hinged tube or trough, and Fig. 3 is a detailed end elevation of said tube or trough.

Referring to the drawings, 1 denotes a boiler 35 having a discharge-tube 2. This boiler is adapted to be placed upon the top of a stove and in the present instance is shown in the form of a tea-kettle.

3 denotes the still, which consists of a shell 40 4, having supporting-legs 5 and a condensing-chamber 6.

7 denotes a discharge-pipe for the condensing-chamber, and 8 the faucet at the end thereof.

45 9 denotes a tube or trough hinged intermediate its ends at 10 and having one end projecting into the condensing-chamber and the other end projecting from without the same.

This tube or trough is preferably curved, as 50 shown, and is formed at its outer end with a

catch-basin 11, formed of an upwardly-projecting flange or strip 12, extending transversely across the end of the trough or tube. Arranged inward of this catch-basin is a lip 13, which when the discharge-tube 2 of the 55 boiler is inserted into the tube or trough 9 projects into the end of said discharge-tube.

14 denotes a faucet communicating with the water-space in the still and having its lower end projecting through an opening 15 60 in the tube or trough 9, immediately above the lip 13.

The parts being assembled upon the stove, as shown in the drawings, the boiler is filled with water, and the shell 4 of the still is also 65 filled with water. As the water within the boiler turns to steam said steam will discharge through the tubes 2 and 9 into the condensing-chamber, which being surrounded by cold water will condense the steam 70 into water, which may be drawn off through the pipe 7 and faucet 8. As the water within the shell becomes heated it may be removed from the open top of the shell and placed within the boiler 1, or the faucet may be 75 opened and a part of the water within the shell run through said faucet onto the lip 13 and through the tube 2 into the boiler. Any water of condensation which may remain in the tube 9 at its outer end is caught 80 by withdrawing the tube 2 from the tube 9 and the basin 11, and by tilting the tube 9 on its hinge this water may run or be let into the condensing-chamber.

From the foregoing description, taken in 85 connection with the accompanying drawings, the construction, mode of operation, and advantages of the invention will be readily understood without requiring an extended explanation.

90 Various changes in the form, proportion, and details of construction may be made within the scope of the invention without departing from the spirit or sacrificing any of the advantages thereof.

Having thus described our invention, what we claim, and desire to secure by Letters Patent, is—

95 1. A still comprising a shell, a condensing-chamber located within said shell and a 100

hinged tube or trough one end of which projects into said condensing-chamber and the other end of which is provided with a catch-basin, substantially as set forth.

- 5 2. A still comprising a shell, a condensing-chamber located within said shell, a tube or trough projecting into said shell, a lip arranged within said tube or trough and adapted to coact with and receive the discharge-tube of the boiler and establish communication between the shell and the tube or trough

whereby water from said shell may be let into the tube of the boiler, substantially as set forth.

In testimony whereof we have hereunto set 15 our hands in presence of two subscribing witnesses.

EDWARD WARREN.
GEORGE W. HEALY.
